UNITED STATES PATENT OFFICE

156,754

DRESS ENSEMBLE

Verone R. Moreno, Washington, D. C.

Application May 27, 1949, Serial No. 2,908

Term of patent 7 years

(Cl. D3—26)

To all whom it may concern:

Be it known that I, Verone R. Moreno, a citizen of the United States residing in Washington, District of Columbia, have invented a new, original, and ornamental Design for a Dress Ensemble, of which the following is a specification, reference being had to the accompanying drawings, forming part thereof.

Fig. 1 is a front view of a dress ensemble showing my new design.

Fig. 2 is a rear view of Fig. 1.

Fig. 3 is a front view of the jacket member of the ensemble shown in Fig. 1, with the detachable cuffs removed.

Fig. 4 is a rear view of Fig. 3.

Fig. 5 is a front view of the dress member of the dress ensemble shown in Fig. 1, with the detachable hem section in the lowest position for evening wear.

Fig. 6 is a rear view of Fig. 5.

Fig. 7 is another front view of the dress member with the detachable hem section applied to the neckline so as to form a cape-like collar on a street-length skirt.

Fig. 8 is a rear view of Fig. 7.

Fig. 9 is a front view of the bodice of the dress.
Fig. 10 is a rear view of Fig. 9.

I claim:

The ornamental design for a dress ensemble, substantially as shown.

VERONE R. MORENO.
